Primary Examiner — Alison M Ofstun*Assistant Examiner* — Evin F Ershock(74) *Attorney, Agent, or Firm* — Gloria Tsui-Yip; Gottlieb, Rackman & Reisman, P.C.(57) **CLAIM**

The ornamental design for a brush as shown and described.

DESCRIPTION

FIG. 1 is a top, left, and front perspective view of a brush of my new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a rear elevational view thereof;

FIG. 7 is a front elevational view thereof; and,

FIG. 8 is a bottom, right, and front perspective view thereof. The broken lines in the drawings depict portions of the brush that form no part of the claimed design.
